LEG SUPPORTING PLATFORM AND EXTENSION FOR ADJUSTABLE CHAIRS

Robert A. Maurer, East Palestine, Ohio, assignor
to The Kenmar Manufacturing Company, East
Palestine, Ohio, a corporation of Ohio

Application December 12, 1951, Serial No. 261,237

3 Claims. (Cl. 155—105)

1

This invention relates to adjustable chairs such as reclining chairs in general and more particularly to leg supporting platforms associated therewith and specifically to an extendible portion of such leg supporting platform.

The principal object of the invention is the provision of a leg supporting platform with an extension for an adjustable chair.

A further object of the invention is the provision of an extension for a leg supporting platform as used on an adjustable chair and operating to extend the effective length of the platform.

A still further object of the invention is the provision of an extension for a leg supporting platform as used on an adjustable chair and comprising a simply operated, economically formed device.

The extension for leg supporting platforms as used on adjustable chairs and disclosed herein comprises an improvement in the art relating to such chairs and particularly with respect to the co-pending application of Fred C. Maurer on Adjustable Chair With Leg Supporting Platform, Serial No. 240,135 filed August 11, 1951 and assigned to The Kenmar Manufacturing Company, wherein an adjustable chair is disclosed with a leg supporting platform mounted adjacent the forward edge of the seat portion for movement from a vertical position beneath the seat portion when the chair is in upright position to substantially horizontal position in front of the seat portion when the chair is in reclining position.

The construction in the said co-pending application works efficiently and is attractive in use and operation but is not entirely satisfactory under all conditions as taller people find the leg supporting platform engaging their legs in the area of the calves whereas the ideal support from such a platform would occur at a point closer to the person's feet.

The present invention discloses a construction like that in the said co-pending application with respect to the chair and the adjusting means and the platform elevating and retracting means and, in addition thereto, illustrates a simple and economical form of platform extension which moves outwardly with respect to the main leg supporting platform when the platform moves into substantially horizontal position, thus providing the extra length necessary and desirable for adequately supporting the user's legs.

The present disclosure relates primarily to the leg supporting platform and the extension thereof and the means mounting the extension

2

on the platform and the means operated by the platform in conjunction with the chair for moving the extension into and out of extended position.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing, wherein:

Figure 1 is a side elevation of an adjustable chair in upright position with parts broken away and parts in section and illustrates the leg supporting platform and extension in retracted position.

Figure 2 is a side elevation of the chair with parts broken away and parts in cross section with the seat portion in reclining position, the platform in horizontal position and the extension in extended position.

Figure 3 is a vertical section taken on line 3—3 of Figure 1.

Figure 4 is a substantially horizontal section taken on line 4—4 of Figure 2.

By referring to the drawings and Figures 1 and 2 in particular it will be seen that an adjustable chair with a leg supporting platform having an extension thereon is disclosed and comprises a base 10 having a pair of spaced arms 11 affixed thereto and arranged to adjustably position a seat and back unit therebetween, the upright portion of which is a back 12 and the horizontal portion of which is a seat 13. The seat and back unit includes a pair of spaced rails 14 positioned beneath the sides of the seat portion 13, the rails 14 serving to position a pair of rods 15—15 transversely of the seat portion 13. The base 10 has a pair of spaced vertical side sections 16—16 positioned beneath the arms 11 and parallel with and adjacent to the rails 14 heretofore referred to. Two pairs of semi-arcuate slots 17 and 18 are formed in the vertical side sections 16—16 in oppositely disposed relation so that the extending ends of the rods 15—15 register therein for sliding movement therein.

It will thus be observed by referring to Figure 1 of the drawings that when the seat and back unit is in position, as shown, with the seat portion 13 in substantially horizontal position, the

rods 15—15 are in the forward ends of the semi-arcuate slots 17 and 18.

It will thus be observed by referring to Figure 1 of the drawings that when the seat and back unit is in position, as shown, with the seat portion 13 in substantially horizontal position, the rods 15—15 are in the forward ends of the semi-arcuate slots 17 and 18.

By referring to Figure 2 of the drawings it will be seen that the rods 15 move to the opposite or rear ends of the semi-arcuate slots 15 and 17 when the seat and back unit is tilted backwardly to reclining position. The front portion of the seat portion 13 is cut away beneath the upper edge thereof so that a leg supporting platform formed of two parts 19 and 20 may be positioned therebeneath in vertical position when the chair is in upright position, as shown in Figure 1 of the drawings. The two parts 19 and 20 of the leg supporting platform are preferably upholstered so that they match the appearance of the seat portion 13 of the seat and back unit of the chair and are of a size and shape so that they conform with the chair lines in upright position, as shown in Figure 1 of the drawings, and do not indicate their presence.

Mechanism is provided, as shown in Figures 1 and 2 of the drawings, for moving the two-part leg supporting platform outwardly and upwardly at such time as the seat and back unit is moved backwardly to reclining position. The mechanism for moving the two-part leg supporting platform comprises a plurality of levers which are pivotally affixed to the one part 19 of the leg supporting platform and which are actuated by the movement of the unitary seat and back portion with respect to the stationary base. The movement is initiated by a pair of oppositely disposed levers 21—21 pivoted midway between their ends by pivots 22—22 to the vertical side sections 16.

The levers 21—21 lie inwardly of the vertical side sections 16 and adjacent the rearmost pair of arcuately formed slots 13. The levers 21—21 are pivoted to the vertical side sections 16—16 so that their uppermost ends, as seen in Figure 1, move on an arc comparable with that of the arcuate slots 18 and the uppermost ends of the levers 21—21 are bifurcated as at 23 so that they may slidably engage the rods 15 at points thereon between the side rails 14 of the seat and back unit and the vertical side sections 16 of the base, as best shown in Figure 4 of the drawings.

By referring again to Figure 1 of the drawings it will be observed that a pair of offset links 24 are pivoted at their rearward ends to the lower ends of the levers 21 by pivots 25—25 and to the upper portions of the leg supporting platform 19 by pivots 26—26. It will be observed that the bottom portion of the side rails 14 of the seat and back unit have recesses cut therein registering with the offset portion of the offset links 24 which permits the rearward ends of the offset links 24 to lie on a plane between the side rails 14 and the vertical side sections 16 while their forward portions lie within the area between the rails 14 of the seat and back unit.

A pair of secondary levers 27—27 are pivoted at their uppermost ends to the inner sides of the side rails 14 by means of pivots 28—28 and at their lowermost ends to a pair of secondary links 29—29 by means of pivots 30—30. The secondary levers 27—27 are also pivoted intermediate their ends to the links 24—24 by means of pivots 31—31 and the foremost ends of the secondary links 29—29 are pivoted to the lower portion of the part 19 of the leg supporting platform by means of pivots 32—32. It will thus be seen that when the seat and back unit is in upright position, as shown in Figure 1 of the drawings, the levers 21 are in approximately vertical position with their bifurcated upper ends 23 engaged upon the rod 15 which is in the upper portion of the arcuate slots 18. The offset links 24 extend between the lower ends of the levers 21 and the upper pivotal attachment points of the leg supporting platform 19.

The leg supporting platform 19 is in vertical position by reason of the positioning of the secondary levers 27 and the secondary links 29. The secondary levers 27 are pivoted to the side rails 14 of the seat and back unit by the pivots 28 and are in substantially vertical position with their lower ends pivoted to the rear ends of the secondary links 29 through the pivots 30. The pivots 31 intermediate the ends of the secondary levers 27 are pivoted to the offset links 24 at a distance spaced from the forward end of these links such that the leg supporting platform 19 is held in vertical position, as shown in Figure 1 of the drawings.

At such time as the seat and back unit is tilted backwardly, as shown in solid lines in Figure 2 of the drawings, the levers 21 move from approximately vertical position to approximately horizontal position as they follow the movement of the rod 15 in the oppositely disposed arcuate slots 18. The opposite ends of the lever 21 therefore move the links 24 forwardly which causes the upper end of the leg supporting platform to move outwardly and forwardly as the links 24 are pivoted by way of the secondary levers 27 and the pivots 28 to the side rails 14 of the seat and back portion. The lower end of the leg supporting platform 19 swings outwardly and upwardly on an arc based on the pivots 26 on the ends of the offset links 24 by reason of the secondary links 29 and the secondary levers 27 to which they are pivoted.

It will thus be seen that the leg supporting platform 19 moves in a predetermined pattern directly responsive to the tilting motion of the seat and back unit and that when the seat and back unit is in reclining position, as shown in solid lines in Figure 2 of the drawings, the platform has moved into substantially horizontal position in horizontal alignment with the forward end of the seat portion 13.

By referring again to Figures 1 and 2 of the drawings it will be observed that the extension portion 20 of the leg supporting platform 19 is mounted immediately below the platform 19 when the same are in vertical position, as in Figure 1 of the drawings, and that it moves outwardly with respect thereto when the platform 19 is in horizontal position as shown in Figure 2 of the drawings.

By referring to Figures 3 and 4 of the drawings the mechanism for accomplishing this movement may be seen. The extension 20 is supported on the platform 19 by a pair of rearwardly extending rods 33—33 which telescopically engage a pair of tubular members 34—34 which are mounted beneath the platform 19. The platform 19 also carries a moving lever 35 pivoted thereto as at 36 and normally lying on a diagonal line with respect to the forward edge of the platform 19, as best seen in Figure 3 of the drawings. The foremost end of the moving lever 35 is pivoted to a bracket 37 on the foremost end of a link 38 which

in turn is pivoted to a bracket 39 on a transverse member 40 extending between the rails 14 of the seat 13. The opposite end of the moving lever 35 is pivoted to a secondary link 41 and the secondary link 41 is pivoted as at 42 to the extension 20.

It will thus be observed that when the outward and upward motion of the platform 19 occurs by reason of the tilting of the seat and back portions of the chair, the platform 19 moves with respect to the transverse member 40 of the seat 13 and thus causes the link 38 to move the moving lever 35 on its pivot 36, which motion is reversed by the moving lever 35 and is imparted to the link 41 which is pivoted to the extension 20 and thereby causes the same to move away from the platform 19. Thus as the platform 19 moves outwardly and upwardly on its arcuate path to approximately horizontal position in front of the seat portion 13 of the chair, the extension 20 also moves outwardly with respect to the platform 19 and assumes its proper position for the desired support of the legs of the person sitting in the chair.

At such time as the seat and back portion of the chair is moved into upright position, as shown in Figure 1 of the drawings, the platform swings downwardly in under the forward edge of the seat 13 and simultaneously the extension 20 moves inwardly into close proximity with the platform 19 as also shown in Figure 1 of the drawings. It will thus be seen that the tilting of the seat and back unit of the chair results in the movement of the platform 19 and in the movement of the extension 20 with respect thereto.

It will thus be seen that the adjustable chair with leg supporting platform disclosed herein meets the several objects of the invention.

It will occur to those skilled in the art that the mechanism is efficient and incapable of becoming inoperative and that it may be inexpensively formed and positioned in the chair in a minimum of space.

Having thus described my invention, what I claim is:

1. In a reclining chair having a leg supporting

platform movable relative thereto, an extension for said platform movably mounted on said platform for movement toward and away from said platform, means for moving said extension with respect to said platform and comprising a moving lever pivoted midway between its ends to said platform, a link connecting one end of said lever to said chair and a secondary link connecting the other end of said lever to said extension.

2. In a reclining chair having a leg supporting platform movable from substantially vertical to substantially horizontal position relative thereto, an extension for said platform, tubular guides on said platform and projecting rods on said extension registering with said tubular guides, means for moving said extension with respect to said platform and comprising a lever pivoted midway between its ends to said platform, a link connecting one end of said lever to said chair and a secondary link connecting the other end of said lever to said extension, said extension being responsive in movement to relative motion between said platform and said chair.

3. A leg supporting platform for a reclining chair having a stationary base and a relatively movable seat portion, levers interconnecting said stationary base, seat portion and said platform to move the same when the seat portion is moved relative to said base portion, an extension mounted on said platform for movement on a plane common thereto and a moving lever pivoted between its ends to said platform and links connecting the opposite ends of said moving lever with said chair and said extension, respectively.

35
